UNITED STATES PATENT OFFICE.

EBENEZER HILL, OF SOUTH NORWALK, CONNECTICUT.

AIR-COMPRESSOR.

SPECIFICATION forming part of Letters Patent No. 700,927, dated May 27, 1902.

Application filed August 17, 1901. Serial No. 72,349. (No model.)

To all whom it may concern:

Be it known that I, EBENEZER HILL, a citizen of the United States, residing at South Norwalk, in the county of Fairfield and State of Connecticut, have invented certain new and useful Improvements in Air-Compressors, of which the following is a specification.

It is frequently necessary in factories to use compressed air at two different pressures—
10 for example, it may be desired to draw air at twenty pounds for cleaning castings and at the same time draw air at ninety pounds for running hoists and tools. Under ordinary conditions drawing air from between the cylinders of a compound compressor reduces the volume of air to such an extent that the interpressure will not be maintained.

This invention relates to a compound compressor so devised that air may be drawn at two different pressures without material reduction of pressure in the interreservoir.

The object is to so arrange the valves and connections of a compressor that when air is drawn at low pressure from between the cylinders the second piston will automatically be rendered partly or wholly inoperative, thus leaving sufficient air between the cylinders to maintain the pressure.

This invention resides in a compound air-compressor having a passage connecting the interreservoir or other part of the duct between the cylinders and a specially-constructed inlet or discharge valve of the second cylinder, whereby on a reduction of pressure between the cylinders this special valve will be held open, so that the action of the second piston will be rendered ineffective and the volume of air which otherwise would be pumped forward by said piston will be reserved to prevent a reduction of volume and a consequent fall of pressure, which would otherwise be incident to the low-pressure demand.

Figure 1 of the accompanying drawings shows an elevation of a part of a compound air-compressor with the first and second cylinders in section. Fig. 2 shows a section of an ordinary inlet-valve. Fig. 3 shows a section of an ordinary discharge-valve. Fig. 4 shows a section of a special inlet-valve. Fig. 5 shows a section of a special discharge-valve. Fig. 6 is a diagram indicating the manner of

using the special inlet-valve at each end to put the second cylinder entirely out of commission. Fig. 7 is a diagram indicating the use of a special discharge-valve at each end to put the second cylinder entirely out of commission. Fig. 8 is a diagram indicating the use of a special inlet-valve at one end and a special discharge-valve at the other end for putting the second cylinder out of commission. Fig. 9 is a diagram indicating the use of a special inlet-valve and a special discharge-valve at the ends of the second cylinder opposite to the arrangement represented by Fig. 65. Fig. 10 is a diagram indicating the use of a special inlet-valve at one end for putting one half of the cylinder out of commission. Fig. 11 is a diagram indicating the use of a special inlet-valve for putting the other half of the second cylinder out of commission. Fig. 12 is a diagram indicating the use of a special discharge-valve at one end for putting that end of the cylinder out of commission. Fig. 13 is a diagram indicating the use of a special discharge valve for putting the opposite half of the cylinder out of commission, and Fig. 14 is a view showing a modified means for operating a discharge-valve when the pressure in the cylinder-interduct is reduced.

The piston 1 in the double-acting first cylinder 2 of the compressor illustrated is connected with the piston 3 in the double-acting cylinder 4 by a rod 5, which is adapted to be connected with steam-pistons in the usual manner. The first and second cylinders are connected by an ordinary interreservoir 6, which may be any desired shape and diameter and which, with the openings to the valve-ports, forms the interduct. The first cylinder at each end has a common inlet-valve 7 and a common discharge-valve 8. The second cylinder is shown with a common inlet-valve 9 at one end and a common discharge-valve 10 at the other end. If the inlet-valve at one end of the second cylinder is held open, that end of the cylinder will be inoperative. Holding the discharge-valve at one end of the second cylinder open will accomplish the same result. The second cylinder is illustrated with a special inlet-valve 11, that will be held open when air is drawn from the interduct, and it is also illustrated with a special discharge-valve 12,

putting an end of the cylinder out of commission is the pressure of air. It is possible to employ gravity, as by means of a weight 44 and lever 45, instead of a spring or air-pressure for this auxiliary force, as represented by dotted outline in Fig. 14. These valves act automatically, and when one is held open the amount of air that would have passed through it and not return is reserved to supply the place of that which is drawn off from the interduct.

If it is desired to render the second cylinder entirely inoperative, one of the above special inlet-valves could be used at each end, as indicated by Fig. 6, or one of the above-described discharge-valves could be used at each end, as indicated by Fig. 7, or a special inlet-valve could be used at one end and a special discharge-valve could be used at the other end of the second cylinder, as indicated by Figs. 8 and 9. If it is desired to put only one half of the second cylinder out of commission, one special inlet or one special discharge valve can be used at either end, as indicated by Figs. 10, 11, 12, and 13.

By means of the simple mechanism described it is possible to furnish air at high and low pressures with a single compressor so as to meet the ordinary demands of a factory.

I claim as my invention—

1. A compound air-compressor having cylinders, pistons, inlet and discharge valves and cylinder-interduct, means for opening a valve of the second cylinder, and a passage so connecting said interduct with the valve-opening means that the pressure in the cylinder-interduct controls the operation of the valve-opening means, substantially as specified.

2. A compound air-compressor having cylinders, pistons, inlet and discharge valves

and cylinder-interduct, means tending to open an inlet-valve of the second cylinder, a passage so connecting said interduct with the chamber of said inlet-valve that the normal pressure in the cylinder-interduct is exerted oppositely to and holds in check the means tending to open said inlet-valve, substantially as specified.

3. In a compound air-compressor having cylinders, pistons, inlet and discharge valves and cylinder-interduct, a valve-piston, means for moving the valve-piston so it will open a valve of the second cylinder, and a passage so connecting said interduct with the valve-piston chamber that the normal pressure in the cylinder-interduct is exerted oppositely to and holds the means for moving the valve-piston, substantially as specified.

4. A compound air-compressor having cylinders, pistons, inlet and discharge valves and cylinder-interduct, a valve-piston, a spring for moving the valve-piston so it will open a valve of the second cylinder, and a passage so connecting said interduct with the valve-piston chamber that the normal pressure in the cylinder-interduct is exerted oppositely to and holds the means for moving the valve-piston, substantially as specified.

5. A compound air-compressor having cylinders, pistons, inlet and discharge valves and cylinder-interduct, a valve-piston, a spring for moving the valve-piston into contact with a portion of a valve of the second cylinder, and a passage so connecting said interduct with the valve-piston chamber that the normal pressure in the cylinder-interduct is exerted oppositely to and overcomes the spring, substantially as specified.

EBENEZER HILL.
